UNITED STATES PATENT OFFICE.

JAMES E. WELCH, OF PETERSBURG, ILLINOIS, ASSIGNOR OF ONE-HALF TO
ALBERT B. BOWMAN, OF ST. LOUIS, MISSOURI.

WHEAT-HEATER.

SPECIFICATION forming part of Letters Patent No. 254,077, dated February 21, 1882.

Application filed July 19, 1881. (No model.)

To all whom it may concern:

Be it known that I, JAMES E. WELCH, of Petersburg, in the county of Menard and State of Illinois, have invented a certain new and useful Improvement in Wheat-Heaters, of which the following is a full, clear, and exact description, reference being had to the accompanying drawings, forming part of this specification.

This device is for heating wheat to prepare it for its subsequent grinding; and this invention consists in one or more shells or chambers contracted at the waist or middle portion, the lower portion of the shell being formed with circumferential ribs or projections, and the upper portion being provided with a conical top, the shell being surrounded by a pipe-coil of approximately the same shape, but larger, so as to provide an annular chamber between the shell and the coil for the passage of the grain. Both the shell and the pipe have steam-induction and water-eduction pipes leading to and from them, and are inclosed within an outer case, between which and the coil is a packing of non-conducting material. The outer case has hoppers at top and bottom for receiving the grain as it enters and is discharged from the heater, all of which will more fully appear hereinafter.

In the drawings, Figure 1 is an axial section of my improved heater. Fig. 2 is an axial section of a modified form thereof.

A is a shell formed with a contracted waist, so as to flare upwardly and downwardly from its center. The lower portion of the shell is provided with downwardly-projecting circumferential projections or ribs *a*, whose upper faces incline outwardly and downwardly, as shown. The upper end, *a'*, of the shell is conical, so that the grain on entering the heater and striking the conical top will be directed into the space C between the shell and a coiled pipe, B, as shown, the pipe conforming approximately to the shape of the shell beneath the conical top. Preferably the annular space C between the shell and pipe is rather larger at the waist C' than elsewhere, so that the grain will not be liable to choke in its passage through the machine.

D is an outer case or cylinder, with top *D'* and bottom *D''* inclosing the shell and pipe. Between the case D and pipe B is a packing,

E, of asbestos or other non-conducting material to prevent the escape of heat.

F is a hopper depending from the top D' of the case D for receiving the grain as it enters 55 through the opening *f* and directing it into the annular chamber C.

At the bottom of the heater is a hopper, G, which receives the heated grain as it passes from the chamber or channel C through the 60 annular series of openings *g*. The grain may pass from the hopper G directly into the hopper of a millstone, or elsewhere, as desired.

A' and B' are steam-pipes passing through the case D and packing E to the shell A and 65 pipe B, respectively, and A² B² are water-discharge pipes for carrying off the condensed water from the cone and pipe, respectively. Said induction and eduction pipes are provided with suitable valves, A³ B³, as shown. 70

The operation of the machine is as follows: The shell A and pipe B are heated by steam admitted through the induction-pipes A' B'. The grain is then fed to the machine through the opening *f* in the top of the case proper, 75 and is directed by the hopper F and the upper end of the cone into the annular channel or chamber C, down which it passes by gravity. As the grain passes down the channel it comes in contact with the projections on the lower 80 part of the shell, by which it is agitated, so that every portion of the grain is subjected to the heating-surfaces of the shell and pipe. Then the grain passes out through the openings *g* from the chamber C into the hopper G, as set 85 forth.

In the modification shown in Fig. 2 the parts are the same as those shown and described in Fig. 1, except that there are three such shells cast in one piece, and having their lower portions each provided with the projections or ribs *a*. I do not confine myself to any number of these shells arranged one above another. 90

Having thus described my invention, the following is what I claim as new therein and desire to secure by Letters Patent: 95

1. In a wheat-heater, the combination of shell A, contracted at the waist and formed with conical top *a'*, and a steam-coil, B, surrounding the shell, as set forth, the lower portion of 100 the shell being provided with downwardly-projecting circumferential ribs, the upper faces of

which are inclined downward and outward, as and for the purpose set forth.

2. The combination of the shell A, having projections a , steam-coil B, conforming thereto, case D, packing E, and induction and eduction pipes $A' B' A^2 B^2$, all arranged substantially as and for the purpose set forth.

3. The combination of shell A, ribs a , coil-

pipe B, annular space C, case D, with hoppers F G, and openings $f g$, packing E, and induction and eduction pipes, for the purpose set forth.

JAMES E. WELCH.
